5 Sheets-Sheet 1

Fig. 1.

This technical drawing illustrates a complex mechanical assembly, possibly a gear train or transmission, with numerous numbered components. The components are labeled with numbers such as 1, 2, 3, 4, 5, 6, 7, 8, 9, 10, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, and 79. The assembly includes various gears, shafts, and housing parts, with some components shown in cross-section to reveal internal details. The drawing is a line drawing with no color.

UNITED STATES PATENT OFFICE

GROVER C. COIL, OF DAYTON, OHIO, ASSIGNOR TO OHMER FARE REGISTER COMPANY, OF DAYTON, OHIO

INTERLOCKING MECHANISM

Application filed June 29, 1928. Serial No. 289,278.

The object of this invention is to provide interlocking mechanism whereby the improper sequence of operations of a register is prevented. In the particular register shown 5 by way of illustration in this application means are provided whereby the register may be normally operated to print a record. If desired, a total representing the sum of all previous registrations may be printed and it 10 is possible to reset the totalizer to zero. I have provided locking and interlocking mechanism whereby the machine is locked against operation if any of the setting means for the register are not properly set. I have 15 also provided spacing mechanism whereby the record paper may be actuated so as to move all of the detail impressions beyond the point where the total impression will be made. Means are further provided whereby the total 20 printing mechanism is rendered inoperative until the spacing mechanism has been fully actuated. I further provide means whereby it is impossible to reset the totalizer until after an impression has been taken therefrom. 25 It is not, however, necessary to reset the totalizer. Locking means are also provided to lock the machine against operation while the impression is being taken from the totalizer. I have also provided means whereby 30 you cannot take a total print or reset to zero unless all money and class levers are in zero position.

Means are also provided whereby the class lever cannot be placed in "no sale" position 35 unless all amount levers or keys are in zero position.

If it is desired to read the total impression it is necessary to release the retaining pawl 40 of the spacing mechanism and to advance the spacing mechanism again.

Summarizing, means are provided whereby you cannot take a total print unless all money and class levers are in zero position. You cannot take a total impression unless 45 you have properly spaced the record paper. You cannot turn to zero until after taking a total print. You cannot read your total print without releasing the retaining pawl and again spacing the record paper. You 50 cannot partly operate the printing knob and

then operate the machine. After starting to take the total impression the spacing mechanism is held locked and so are the said levers or keys. All money levers must be in zero position before recording a "no sale" trans- 55 action.

With these and other objects in view as will be more fully explained in the detailed description which follows, I have shown the preferred construction of my invention in 60 the drawings, in which—

Fig. 1 is an elevational view from the right-hand side of the machine, parts being broken away for the sake of clearness.

Fig. 2 is a detailed view of the mechanism 65 mounted on the outside of the right sidewall of the machine and showing in detail the parts omitted from Fig. 1.

Fig. 3 is an elevational view of the mechanism mounted on the left sidewall of the ma- 70 chine.

Fig. 3A is an elevational view of the releasing lever and retaining pawl of the spacing mechanism.

Fig. 3B is an elevational view of the chan- 75 neled disk of the spacing mechanism.

Fig. 4 is an elevational view partly in cross-section on the line 4—4 of Fig. 6 looking in the direction of the arrows.

Fig. 5 is an elevational view partly in 80 cross-section of the mechanism shown in Fig. 7.

Fig. 6 is a plan view of the machine, cer- 85 tain parts being omitted for the sake of clearness.

Fig. 7 is a plan view of the "no sale" lock- 85 ing mechanism.

Fig. 8 is a plan view of the frame through which the setting levers pass and showing another feature of the "no sale" locking 90 mechanism,

Fig. 9 is a perspective view of the sliding members used in connection with a "no sale" transaction.

The machine on which my locking mecha- 95 nism has been shown by way of illustration is fully described in the application of Albert S. Wheelbarger and Grover C. Coil, Serial No. 65,532, filed October 29, 1925, for Ticket printing, issuing and recording ma- 100

chines, and in their application Serial No. 238,662 for Totalizers and printing means therefor, filed December 8, 1927. In these applications a hand crank is shown whereby the machine may be operated, although, of course, it may be operated by a motor as is well known in the art. The hand crank 1 is rigidly mounted on a shaft 2 mounted in the right sidewall 3 of the machine, which shaft 10 has secured thereto a gear 4 which meshes with gears 5 and 6 respectively. The gear 6 is secured to a segmental gear 7 which has a disk portion 8. A pinion 9 is mounted on a shaft 10, which shaft 10 is provided with a platen 11. The pinion 9 meshes with and drives a pinion 12 mounted on a shaft 13 which shaft carries a matrix 14 which is a conventional electroplate.

The pinion 5 is mounted on a shaft 15 which shaft carries a cam 16 and a pinion 17, which latter pinion meshes with and drives a pinion 18 on a shaft 19 which is the main driving shaft of the machine. The shaft 19 has secured thereto a disk 20 having a V-shaped notch 21. Secured to the disk 18 is a cam 22. A lever 23 is pivoted on the left sidewall 24 of the machine by means of a stud pin 25 which lever carries pins 26 and 27 respectively on which are mounted rollers 28 and 29 respectively which engage the cams 16 and 22 respectively so as to rock the lever 23 clockwise and then anti-clockwise to actuate the rod 30 operatively connected thereto by means of a pin 31, which rod 30 is connected to a part of the totalizer actuating arm 32 by means of a pin 33. The totalizer mechanism, of itself, forms no part of this invention and need not be further described.

The gear 6 is provided with a wrist pin 34 which actuates a pitman 35 connected to an oscillating printing carrier 36 by means of a wrist pin 37, the oscillating printing carrier being mounted on a shaft 38. This printing carrier is provided with a plurality of platens 39 and 40, both of which platens cooperate with printing wheels 41. The platen 40 is provided for the purpose of printing a ticket but as the ticket printing means forms no part of this invention it is not shown nor will it be described.

The record paper 42 is wound onto a shaft 43 which shaft is advanced each time the machine is operated by means of the wrist pin 37 moving an L-shaped lever 44 to the left as viewed in Fig. 2, which lever is mounted on a shaft 45. This lever engages a lever 46 rotatably mounted on the shaft 43, which lever carries a pin 47 on which a double-nosed pawl 48 is mounted. The double-nosed pawl 48 is provided with a slot 48' through which passes the pin 47 and with an extension 49 which carries a pin 50. A spring 51 connects the pins 50 and 47 so as to cause either nose of the pawl to engage the ratchet 52 secured to the shaft 43. A

spring 53 normally retains the lever 46 against a pin 54 mounted on the right sidewall 3 of the machine.

The setting levers or keys 79 are secured to gears 56 which mesh with pinions 57 on the printing wheels 41. It is by this means that the printing wheels are set so as to print a desired numeral or other indicia on the ticket and record paper. The gears 56 are also connected with gears 57 which gears are the actuating means for the totalizer wheels 58. As before stated, the means for actuating the totalizer, however, forms no part of this invention and a detailed description of the totalizer actuating means is not believed to be necessary.

A shaft 59 is secured to the sidewalls of the machine and on this shaft are mounted levers 60 provided with pins 61 which carry small rollers 62 which engage between the teeth of the gears 56. These rollers are pressed toward the gears 56 by means of springs 63 secured to the levers 60 and to a shaft 64 secured to fixed parts of the machine. A bar 65 passes behind each of the levers 60, which bar is above the rollers 62 and the bar 65 is connected to levers 66 secured to the shaft 59, which shaft carries arms 67 (Fig. 2) and 68 (Fig. 4). The arm 67 is provided with a pin 69 to which is secured a rod 70 provided with a slot 71 which receives a pin 72 carried by the right sidewall of the machine. The rod 70 is also provided with a forwardly extending projection 73 provided with a lug 74 which, when any of the levers are in such a position that the rollers 62 are on the end of any of the teeth of the gears 56, is projected into the recess 75 in disk 76 secured to the shaft 15, thereby locking the machine against operation. The arm 68 is provided with a lug 77 and a pin 78 which rides on the periphery of the disk 117 to limit the downward movement of the arm 68.

When it is desired to take an impression from the totalizer it is first necessary to move all of the levers or keys representing price or class to zero or home position. The money levers are indicated in Fig. 8 by the reference characters 79 and the class lever is indicated by the reference character 80. In a ticket-issuing machine for use on railways the class lever 80 may be used to indicate the various classes of fare such as half fare, round trip, etc., but in cash registers for use in stores the class lever 80 would be used to indicate the various classes of transactions such as "no sale", "charge", or it might be used to indicate the clerk's number such as "A", "B", etc. The money keys or levers 79 may be placed in zero position as shown in Fig. 8 at any time except when the machine is being operated but as each of these levers is moved to zero position it engages a cam surface 81 on a sliding member 82 which is nor-

5 mally urged to the left by means of spring 83 engaging a pin 84. These sliding members are best shown in Figs. 5 and 8, and it should be noted that there is one sliding member 82 for each of the money levers. The class lever 80 can now be moved to the position shown in Fig. 8 which corresponds to the position in which it should be placed to indicate that money is being paid out, which is 10 generally indicated by the words "no sale". If no sale is being made all of the money levers should be in zero position, and it is impossible to move the class lever 80 to "no sale" position unless all of the money levers 15 are in zero position for the lever 80 will strike against the shoulder 85 of any one of the money levers 79 unless each of the sliding members 82 have been moved to the right as viewed in Fig. 8 by its money lever 79. 20 If all of the money levers are in zero position and the shoulders 85 have been moved out of the path of movement of the class lever 80, it can be moved into the position shown in Fig. 8, which is the "no sale" position, but as it is so moved it strikes against the cam surface 86 of the locking member 87, best shown in Fig. 7, moving the same to the left. The locking member 87 is provided with L-shaped slots 88 through which the 25 money levers 79 pass when being moved to zero position. When all of the money levers are in zero position and the class lever has been moved to its "no sale" position the locking member 87 locks each of the money 30 levers in its zero position by its shoulders 89 engaging behind the said money levers. The locking member 87 is provided with slots 90 which receive pins 91 secured to the frame of the machine, which pin and slot connection 35 guides the locking member 87 in its sliding movement. The locking member 87 is normally urged to the right as viewed in Fig. 7 by means of a spring 92 secured to a pin 93 carried by the locking member and a pin 40 94 carried by a stationary part of the machine. The locking member 87 is also provided with an extension 95 which has a slot 96 which receives a pin 97 carried by a fixed part of the machine. The extension 95 of 45 the locking member 87 is provided with a downwardly extending arm 98 which engages, when the locking member is moved to the left as viewed in Fig. 7, the beveled surface 99 of the locking pawl 100 pivoted on a pin 101 carried by the left sidewall 24 of the machine. This pawl 100 is normally urged in an anti-clockwise direction by means of a spring 208 and is stopped in its counter-clockwise movement by means of the pin 50 78 on the lever 68. The forward end of the pawl 100 normally engages a pin 102 carried by a lever 103 rotatably mounted on the shaft 45, which is the same shaft that carries the gears 56. The lever 103 is a part of the printing mechanism for the totalizer. It is ob-

vious that the pawl 100 holds the lever 103 against operation unless all of the money levers are in zero position and the class lever is in "no sale" position, but when all of these levers are in the said positions the locking 70 member 87 is moved to the left as viewed in Fig. 7 and raises the pawl 100 out of engagement with the pin 102 thereby freeing the lever 103.

75 Before taking an impression from the totalizer it is also necessary to advance the record paper 42. It will be remembered that the record paper 42 receives its impression between the platen 39 and type wheels 41 whereas the printing impression from the totalizer is made by the totalizer printing wheels 58. It is, therefore, necessary to advance the record paper to the left as viewed in Fig. 1 a distance sufficient to move all of the printed impressions from the type wheels 41 to a point to the left of the printed impression that will be made from the totalizer type wheels 58. The paper is advanced by operating the lever 104 which is attached to a ratchet member 105 by means of a sleeve 106. The ratchet member 105 is provided with teeth 107 and a relatively deeper depression 108. A conventional full stroke mechanism 109 works in conjunction with the ratchet member 105 so as to insure a full operation 90 of the ratchet member 105 by the hand lever 104. The ratchet member 105 is provided with an extension 110 which carries a pin 111 to which is secured a pawl 112 normally held in the position shown in Fig. 3 by means of a spring 113. This pawl actuates a ratchet 95 114 rotatably mounted on a shaft 115 and is held against retrograde movement by a locking pawl 116. Secured to the ratchet 114 is a chambered disk 117 provided with a circular channel 118 having a radial outlet 119. The chambered disk 117 is also provided with a cam depression 120. A pawl 121 is pivoted on a pin 122 carried by the left sidewall 24 of the machine, which pawl is provided with an arcuate lug 123 which rides on the periphery of the disk 117 and is pressed downwardly by means of a spring 124 mounted in a stud 125 carried by the left sidewall of the machine. As heretofore mentioned the lever 103 carries a pin 102 which pin normally lies in the circular channel 118, but if the disk 117 is rotated so that the radial outlet 119 lies in the path of movement of the pin 102 when the lever 103 is rotated clockwise the pin 102 100 may pass out of the disk 117 thereby permitting the lever 103 to be actuated.

105 The spacing mechanism, therefore, normally locks the lever 103 against operation and it can only be freed from its locked position by the actuation of the spacing mechanism. When the hand lever 104 is actuated so as to partially rotate the ratchet member 105 anti-clockwise as viewed in Fig. 3 the pawl 112 actuates the ratchet 114. As the 110 115 120 125 130

hand lever 104 is moved back to normal position rotating the ratchet member 105 clockwise as viewed in Fig. 3 the holding pawl 116 holds the ratchet 114 against retrograde movement. Normally 12 operations of the hand lever 104 are required in order to bring the radial outlet 119 in such a position that the pin 102 can pass outwardly therethrough. When this position is reached the cam depression 120 is beneath the truocate lug 123 of the pawl 121 and the spring 124 pushes the said pawl downwardly so that the pawl engages the lug 126 of the ratchet member 105, locking the ratchet member 105 against further operation.

If it should at any time be desired to release the locking pawl 116 this may be accomplished by engaging the hand lever 127 pivoted on the frame of the machine by a pin 128, which hand lever carries a pin 129 which is seated within an open slot 130 of the holding pawl 126. The hand lever 127 is normally urged against such action, however, by means of a spring 131 and the holding pawl 116 is normally urged into engagement with the ratchet 114 by means of a spring 132. As soon as the holding pawl 116 is disengaged from the ratchet 114 a spring 133 (Fig. 6), which is secured to the left sidewall 24 and to a disk 134 which disk is rigid on the shaft 115, rotates the ratchet member 114 to home position where it is stopped by the pin 102 engaging a pin 135 carried by the disk 117 and extending within and terminating the circular channel 118. It is, therefore, obvious that the lever 103 is locked against operation unless all of the money levers have been placed in zero position and the class lever in "no sale" position and unless and until the spacing mechanism has been fully operated. The actual spacing of the paper is accomplished by means of the shaft 45 to which the ratchet member 103 and sleeve 106 are secured. The shaft 45 carries on the opposite side of the machine a lever 136 having an outwardly extending toe 137 which engages the lever 44 which actuates the means to actually space the paper. This lever 136 is provided with an upwardly extending arm 138 which is provided with a cam surface 139 which engages the pin 69 on the rod 70, depressing the said rod so as to lock the disk 76 and the shaft 15. The machine is therefore locked against operation while the spacing mechanism is being actuated, and is locked against operation unless all of the money levers and the class lever are in exactly their correct positions so that the rollers 62 will lie between the teeth of the gears 56.

Even if the paper has been properly spaced it is not necessary to take a total impression. The operator might desire to take a total impression and perform all operations necessary to release the total printing mechanism but if he then changed his mind and decided

that he did not care to take the total impression he could again operate the machine and when he did so the holding pawl 116 would be released and the disk 117 which forms an essential part of the spacing mechanism would be returned to normal position. As shown in Fig. 3 the main shaft 15 is provided with two cams 140 and 141. The cam 140 controls a lever 142 which is pivoted on a shaft 143 and carries a roller 144 which roller engages the cam 140. The roller 144 is urged into engagement with its cam by means of a spring 145 secured to the said lever 142 and to a pin 146 carried by the left sidewall 24 of the machine. The upper end of the lever 142 is bifurcated and the bifurcated part thereof receives a pin 147 carried by a bell crank lever 148 pivoted on a pin 149. The lever 148 is also provided with a lug 150 and with a forwardly extending arm 151. The lug 150 is rotated counter-clockwise around the pin 149 when the machine is operated and then engages the lower end of the holding pawl 116 disengaging the upper end of the same from the ratchet 114.

As a matter of fact it is not necessary to even complete the spacing operation when it has once been started but it is necessary to make a complete stroke of the hand lever 104. At any time after the hand lever 104 has made one complete stroke the cam surface 139 of the arm 138 releases the pin 69 and the machine could be operated as described above so that the holding pawl 116 would free the spacing mechanism and it would be reset to home position.

When the money levers are in zero position and the class lever is in "no sale" position and when the spacing mechanism has been fully operated, the total printing impression may be taken. This is accomplished by rotating the hand knob 152 secured to a shaft 153 which carries a disk 154 which disk is provided with a V-shaped notch 155 similar to the notch 21 in the disk 20 carried by the shaft 15. The disk 154 carries a wrist pin 156 to which is connected a pitman 157 which is attached to a pin 158 on a lever 159 pivoted on a pin 160 carried by the left sidewall of the machine. The lever 159 is bifurcated at its upper end and receives a pin 161 carried by the lower end of the lever 103.

A sliding plate 162 is provided with slots 163 which receive pins 164 carried by the left sidewall 24 of the machine. This sliding plate is provided with V-shaped ends to conform to the notches 21 and 155. As the machine is being operated the righthand end of the sliding member 162 will ride on the periphery of the disk 20 which will force the lefthand projection thereof into the notch 155 and lock the printing mechanism against operation. It is obvious, therefore, that the printing mechanism is locked unless all of the money levers are in zero position and

the class lever is in "no sale" position and unless and until the spacing mechanism has been fully operated and is also locked when the main drive shaft 15 is being operated.

5 If the disk 20 is in the position shown in Fig. 4 and if all other things necessary to permit the operation of the printing mechanism are correctly positioned the knob 152 may be rotated, but when it is, the sliding member 162 is pushed to the right as viewed in Fig. 4 locking the disk 20 and the main drive shaft 15 against operation and the left-hand end of the sliding member 162 rides on the periphery of the disk 154. The lever 159 is provided with a slot 165 which receives a shaft 166 which carries a pinion 167 which meshes with a rack 168 mounted on a shaft 169 (Figs. 3 and 4). The shaft 166 also projects through slots 211 in the sidewalls of the machine, the slots 165 and 211 being the guiding means for the said shaft 166. The shaft is actuated by an arm 170 connected to a lever 171 by means of a spring 172. The lever 171 carries a roller 173 which is actuated by the cam 141. The lever 171 is mounted on the shaft 143 and the roller 173 is normally held in engagement with its cam by means of a spring 174.

30 The operation of the printing mechanism is as follows: As the knob 152 is rotated in a clockwise direction as viewed in Fig. 3 and in an anti-clockwise direction as viewed in Fig. 4, the disk 154 is rotated in an anti-clockwise direction as viewed in Fig. 4 moving the lower end of the lever 159 to the right while the cam 175 mounted on the shaft 153 engages the arm 176 of the lever 171 rocking the shaft 169 and rack 168. While the rack 168 is being so moved the shaft 166 is being moved by the lever 159 to the left as viewed in Fig. 4 so that the platen 177 mounted on the shaft 166 moves the record paper 42 which passes over the said platen into engagement with the type wheels 58 of the totalizer so that an impression of the total amount registered on the totalizer wheels is transferred to the said record paper. The totalizer wheels are inked by an inking roller 178. A locking pawl 179 is mounted in the path of movement of the cam 175 to prevent retrograde movement.

55 It is impossible to reset the totalizer until after the printing operation from the totalizer has been completed for the reason that the arm 180 of the bell crank lever 181 prevents the resetting gear 182 being brought into mesh with the idler gear 183 which idler gear is operatively connected with the printing wheels 58 of the totalizer. The hand knob 184 is provided with a tongue 185 which normally is seated within a groove 186 in a boss 187. The hand knob 184 is secured to a shaft 188 and a spring 189 is interposed between the resetting gear 182 and the left side-

wall 24 of the machine which spring normally urges the tongue 185 into the groove 186 provided the said tongue and groove are in alignment with each other, thereby locking the hand knob 184 against rotation. The 70 arm 180 normally lies beneath the shaft 188 and between the sidewall 24 and the gear 182 so that it is normally impossible to move the gear 182 to the left as viewed in Fig. 6 so as to bring it into mesh with the idler gear 75 183.

A sliding bar 190 (Fig. 4) is provided with a slot 191 which receives a pin 192 carried by the sidewall 24 of the machine. This pin and slot connection guides the righthand end of the sliding bar 190 which bar is in the path of movement of the lever 103 and is connected to the bell crank lever 181 by means of a pin 193. When the printing impression is being made the lever 103 moves clockwise and engages the shoulder 195 of the sliding bar 190 moving it to the left as viewed in Fig. 4 and rotating the bell crank lever 181 mounted on the shaft 196 in a counter-clockwise direction so as to remove the arm 180 below the teeth of the gear 182 so that the said gear may be moved by means of the hand knob 184 to the left as viewed in Fig. 6 into mesh with the gear 183. When the sliding bar 190 is thus moved to the left as viewed in Fig. 4 it is retained in that position by the lug 197 of the bell crank lever 198 engaging the recess 194 in the sliding bar 190, the said lug 197 being urged toward the bar 190 by means of a spring 199 connected to an arm 200 of the bell crank lever 198 and to the pin 192. 90

100 The operator is now free to pull outwardly on the knob 184 so as to bring the gear 182 into mesh with the gear 183 and when he so moves it, the righthand end of the shaft 188 as viewed in Fig. 6 is moved out of holding engagement with the lever 201, which lever must be pulled outwardly in order to permit the resetting of the totalizer. However, the resetting mechanism for the totalizer forms no part of this invention and as it is fully shown and described in the co-pending application of Albert S. Wheelbarger and Grover C. Coil, Serial No. 238,662, the description thereof will not be repeated in this application. 105

110 From the above description, it is obvious that the totalizer is locked against resetting until the impression has been made from the totalizer. It is, however, not necessary to reset the totalizer even though a total impression has been made, for if the machine is again operated the lug 150 on the lever 148 will engage the arm 202 of the bell crank lever 198 and will raise the lug 197 out of engagement with the recess 194 of the sliding bar 190, and the spring 203 attached to the pins 193 and 192 will pull the sliding bar 190 into the position shown in Fig. 4 and 115 130

thereby bring the arm 180 upwardly against the shaft 188, thereby locking the gear 182 from being moved into engagement with the gear 188.

63. As before mentioned, the disk 117 forming a part of the spacing mechanism may be released by disengaging the pawl 116 from the ratchet 114. It may be released by operating the hand lever 127. Obviously, this hand lever is always within the reach of the operator and he could disengage the said pawl and ratchet at any time he pleased. It will be further remembered that the pin 102 carried by the lever 103 passes out of the radial outlet 119 during the printing operation. While the said pin 102 was outside of the disk 117, if the operator operated the lever 127 the disk 117 would tend to be reset by the spring 133 so that the radial outlet 119 would no longer be in the path of movement of the pin 102 and it would, therefore, be impossible to complete the taking of the impression from the totalizer. Means are, therefore, provided to prevent the resetting of the disk 117 during the taking of the impression from the totalizer. To this end the disk 104, rigidly secured to the shaft 115 is provided with an arcuate surface 204 which abuts against the surface 205 of the lever 203 which is secured to the lever 103 thereby locking the disk 117 against rotation. It is, therefore, impossible to actuate the spacing mechanism while a total impression is being taken for the reason that it has already been activated as far as possible. The lever 121 and lug 122 prevent further operation and it cannot be effectively released because the disk 104 and lever 203 prevent retrograde movement.

64. When the total impression is made on the record paper it is not possible to read the total for it is not in a position where it can be seen. It is, therefore, necessary to advance the record paper so that the total impression thereon will be adjacent the sight opening 207 in the frame of the machine. The paper will be so advanced after taking the total impression by releasing the spacing mechanism and again advancing the record paper so as to bring it in line of sight through the opening 207.

65. If any of the keys or levers 55 are not in correct position it is impossible to take a total impression for the reason that the roller 62 will not lie between the teeth of the gear 56 and the shaft 59 will have been moved in a counterclockwise direction as viewed in Figs. 1 and 4 thereby lowering the lug 77 into engagement with the shoulder 209 of the lever 103. Furthermore, if the operator has started to take his total impression all of the keys are locked against operation. As soon as he starts to take his total impression the lever 103, as shown in Fig. 4, is rotated in a clockwise direction so that the surface 210 of the

lever 103 lies immediately beneath the lug 77 thereby preventing the depression of the arm 68 and the consequent rotation of the shaft 59, and, by means of the lever 65, locking all of the rollers 62 into engagement with the teeth of the gears 56, to which the key levers are secured.

I desire to claim broadly the interlocking means for a machine whereby the various operations must be made in a definite sequence, which sequence may, however, in part be varied to suit the desires of the operator. I realize that many changes may be made in the specific embodiment shown by way of illustration in this application and I, therefore, desire to claim the invention broadly regardless of the changes that may be made in the specific construction thereof except as I may limit myself in the appended claims.

Having described my invention, I claim—

1. In a register, a plurality of money keys and a class key each adapted to be set to a plurality of operative positions and means whereby said class key is locked out of "no sale" position unless all of said money keys are in zero position.

2. In a register, a plurality of money keys and a class key each adapted to be set to a plurality of operative positions, means whereby said class key is locked out of "no sale" position unless all of said money keys are in zero position and means whereby said money keys are locked in zero position when said class key is in "no sale" position.

3. In a register, a spacing mechanism for record paper, actuating means for said spacing mechanism, means to control the extent of operation of said actuating means, means tending to return said controlling means to its normal position, means normally preventing such return movement when the spacing mechanism is being actuated, and means to release said last mentioned means at will so that said controlling means will be returned to its normal position.

4. In a register, a spacing mechanism for record paper, actuating means for said spacing mechanism, means to control the extent of operation of said actuating means, means normally preventing return movement of the controlling means when the spacing mechanism is being actuated, and means to release said last mentioned means at will so that said controlling means may be returned to its normal position.

In testimony whereof I affix my signature,
GROVER C. COIL.
